eert de Bretton

UNITED STATES PATENT OFFICE.

GEERT DE BRETTON, OF NEW ORLEANS, LOUISIANA, ASSIGNOR TO HIMSELF AND JOSHUA E. VOSE, OF SAME PLACE.

IMPROVED TRAVELING-TRUNK.

Specification forming part of Letters Patent No. 81,756, dated September 1, 1868.

To all whom it may concern:

Be it known that I, GEERT DE BRETTON, of the city of New Orleans, parish of Orleans, and State of Louisiana, have invented a certain new, useful, and Improved Traveling-Trunk; and I do hereby declare the following to be a full, clear, and exact description of the same, reference being had to the annexed drawings, making a part of this specification, in which—

Figure-1 is a front and Fig. 3 an end view of the same when closed; Fig. 2 a front and Fig. 4 an end view of it when open.

The very great inconvenience and annoyance resulting from the necessity of having to lift out the tray of trunks, as ordinarily constructed, in order to secure access to any article below the same, or, if there be no tray, from being obliged to take out everything lying above the sought-for article in order to reach the same, is such familiar knowledge that a bare reference to it is sufficient to indicate the importance of my improvement, which totally avoids the said inconvenience.

The chief object, in fact, of my improvement is to accomplish such end, and I do it by constructing a trunk in parts or sections, which, when the trunk is open, present a system of shelves throughout the whole of its interior, which are as easily accessible as the shelves of a wardrobe, closet, or any other like thing, and secure a compartment for soiled clothes, in which they can be kept entirely separate from everything else in the trunk.

Another annoyance of such magnitude as to amount to a positive evil that is inseparably incident to the use of trunks as commonly made arises out of the use of cloth and leather straps for holding the cover of the trunk in an upright position when the trunk is open, and for re-enforcing the lock when the trunk is closed by partially encircling the same in the way of bands that are secured by buckles after they have been tightly drawn. A rupture of the cover-sustaining straps not unfrequently entails the breaking or tearing off of the hinges of the trunk; and there is probably not a person who has had to deal with trunks or use them who has not been more or less troubled and vexed by the yielding of the buckles or

outside straps, or by the slipping of their ends between the cover and the body of the trunk in the act of shutting down the former to close the latter. By the substitution of metallic straps of peculiar construction and arrangement, in lieu of cloth and leather, in the fabrication of the above appliances, I remedy this latter evil as completely as the first to which I have adverted.

My invention will be better and more quickly understood by referring to the drawings, upon which at all the figures the same letters denote the same parts.

At Fig. 3 my improved trunk is represented as when closed in an end view; and it will be perceived that in the upper front part of the lower portion or body proper of the same there is a sectional division into a distinct part, embracing the front upper corner of the body proper and constituting about one-fourth of the same, and marked D. This part may, however, obviously be made slightly smaller or more capacious and still be substantially the same thing, it being only necessary so to order its dimensions as that its rear side shall never go back quite to the center of the trunk, and thus prevent the proper placing of the handles. At the upper rear corner of part D it is hinged at three points, a, at least, to the contiguous front corner of the body proper, so that it can be turned over into the position that is shown most clearly at Fig. 4. The lower rear corner of part D is curved or rounded in order that this part may the more readily and smoothly pass over the clothes that are in that part of the trunk-body proper that is immediately below it in its articulation upon its hinges in the one direction or the other, or as it is opened or closed, a corresponding formation being of course made in the angle in the two ends of the trunk into which this corner fits.

The top of part D, when it occupies the position shown at Figs. 2 and 4, constitutes a shelf, and the space above it may be divided by a transverse partition, 1, into two compartments, E and F; or any number of compartments may be created by a multiplication of such partitions, which compartments, whatever be their number, should be covered by

doors provided with hinges and proper fastenings to prevent the falling out of whatever is placed within them whenever part D is turned down into the position as shown at Fig. 3 preparatory to closing the trunk.

Across that portion of the body proper of the trunk that is behind the part D when that part is down, as at Fig. 3, a shelf, b, is introduced a little above the bottom of said part, as is clearly shown at Fig. 2, the object of this arrangement being to bring into view and make more accessible such articles as may be packed below such shelf and in the rear part of the trunk.

Below the shelf b there is no partition or division of the trunk, which hence affords sufficient space for the packing of such articles as are too large to be bestowed on shelves or in the smaller compartments above. The space between shelf b and the top of the body proper of the trunk may be subdivided, as shown, into compartments G and H, or in any other manner that may be deemed desirable, it being understood that, as in part D, whatever the number of compartments, each is to be provided with a door. A bonnet-box can perhaps be more properly introduced on shelf b than anywhere else in the trunk.

It will thus be seen that when the part D occupies the position as shown at Figs. 2 and 4 a series of shelves, conveniently subdivided, make it easy to reach everything in the trunk without any general disturbance of its contents, and that consequently my first object is completely attained.

Metallic facings c are employed in the ordinary manner to cover and conceal all the external joints of the trunk, as shown at Figs. 1 and 3.

The trunk as thus far described in one sense constitutes a whole or perfect trunk, and hence the cover A may not improperly be designated an "extra" cover. This cover may be provided with any number of compartments, and in it, if deemed desirable, may be kept soiled clothes, quite away from contact with everything else in the trunk. At each end of the cover A is placed a curved metallic supporting-bar, B, properly secured thereto, which fits into a similarly-curved sheath, B', that is attached externally upon each end of the trunk-body proper, as shown at Figs. 3 and 4.

The bars B may be so constructed as to hold the cover A at any intermediate position between an upright and a closed one, and they are completely exempt from all the objectionable characteristics of the ordinary appliances employed for preventing trunk-covers from falling backward.

The hasp J of the lock must be sufficiently

long to extend from the cover A, to which it is securely fastened at its upper end, below the part D, so as to overlap the same and reach the lock, which is placed substantially as shown at Fig. 1. This hasp should be hinged or have an articulating joint at some point not far below the top of part D, and, if found desirable, a pin, K, may project from its under side, so as to take in a hole in the front of part D. The hinge in the joint in the hasp provides a means for throwing the same, when the trunk is open, over the upper edge of cover A, and thus out of the way.

On each side of the hasp I place a metallic strap, C, as adjuncts to the lock and hasp or substitutes for the ordinary leather straps upon the outside of trunks, which are pivoted at their upper ends to the front part of cover A and secured by a screw-pin into connection with a novel socket below part D whenever the trunk is closed, at their lower ends, thus in effect subserving the purpose of two additional locks, while in point of fact there is but one key-lock required or used on the trunk.

When the trunk is to be opened the lower extremities of straps C are disconnected from the socket below part D and brought up and secured in similar appliances near hasp J at its upper end, so that they can never be caught between the lower edge of the cover and the upper edge of the body of the trunk, as is the case with leather straps.

My improved trunk may be covered and finished externally in any usual manner, and it may be strengthened by any approved method or means commonly employed for such purpose, and rollers may be applied underneath it, as in the case of all trunks.

Having thus described my invention, what I claim, and desire to secure by Letters Patent, is—

1. The combination of part D with the trunk-body proper, when these parts are united, constructed, and arranged so as to be convertible into a system of shelves, substantially as herein described, for the purpose set forth.

2. The above combination, in combination with the extra cover A, when the several parts are united, constructed, and arranged for conjoint operation substantially as described, for the purpose set forth.

3. The hasp J and metallic straps C, when severally constructed as described, in combination with a trunk provided with a part, D, and an extra cover, A, substantially as herein described, for the purpose set forth.

GEERT DE BRETTON.
